(57) **CLAIM**

The ornamental design for a wheel with carriage, as shown and described.

DESCRIPTION

FIG. 1 is a top front perspective view of a wheel with carriage shown in an environment of use.

FIG. 2 is a top front perspective view thereof.

FIG. 3 is a front view thereof.

FIG. 4 is a rear view thereof.

FIG. 5 is a left-side view thereof.

FIG. 6 is a right-side view thereof.

FIG. 7 is a top view thereof; and,

FIG. 8 is a bottom view thereof.

The broken lines shown in FIG. 1 are for purposes of illustrating environmental subject matter only and forms no part of the claimed design; the additional broken lines shown in FIGS. 1-8 are for purposes of illustrating portions of the wheel with carriage that forms no part thereof.

1 Claim, 5 Drawing Sheets
